UNITED STATES PATENT OFFICE.

JOHN J. HENNESSEY, OF MILWAUKEE, WISCONSIN.

COMBINED FRICTION AND DIRECT-ACTING DRAFT-RIGGING.

SPECIFICATION forming part of Letters Patent No. 717,678, dated January 6, 1903.

Application filed November 15, 1902. Serial No. 131,459. (No model.)

To all whom it may concern:

Be it known that I, JOHN J. HENNESSEY, a citizen of the United States, residing in Milwaukee, in the county of Milwaukee and State of Wisconsin, have invented a new and useful Improvement in a Combined Friction and Direct-Acting Spring Draft-Rigging, of which the following is a specification.

My invention relates to friction spring draft-rigging.

The object of my invention is to provide a combined friction and direct-acting spring draft-rigging of a simple, compact, strong, efficient, and durable construction which may be cheaply manufactured and readily and conveniently applied to the car.

My invention consists in the means I employ to accomplish this result—that is to say, it consists, in connection with a draw-bar and draft-iron in line therewith having a straight friction-face on one side and double-incline friction-faces on its opposite side, a transversely-movable friction-block having double-incline friction-faces engaging the double-incline friction-faces on the draft-iron, and a transversely-arranged spring acting against said friction-block, of a longitudinally-arranged or direct-acting spring and followers therefor on the opposite side of the draft-iron from said transversely-movable friction-block, so that the draft-iron is located centrally and directly between the direct-acting spring and the transversely-acting spring and its friction-block, the draft-iron having wings for operating the followers of the direct-acting spring.

It also consists, in connection with these parts, of a pair of side plates or stop-castings secured to and between the draft-timbers or center sills of the car and provided with suitable transverse guides for the transversely-movable friction-block and a longitudinal case or guide for the followers of the longitudinal or direct-acting spring.

It also consists in providing said side plates or stop-castings with laterally-removable transverse bolts for securing the same together and which also serve as removable stops for the followers of the longitudinally-acting spring, so that said spring and the followers therefor may be inserted and removed through the open end of the guide when such

removable stop-bolts are taken out and so that the draft-timbers or center sills will not interfere with the removal of said bolts. 55

It also consists in the novel construction of parts and devices and in the novel combinations of parts and devices herein shown or described.

In the accompanying drawings, forming a part of this specification, Figure 1 is a vertical longitudinal section of a combined friction and direct-acting spring draft-rigging embodying my invention, the section-line being indicated by the line 1 1 on Fig. 2. Fig. 2 is a plan view showing some of the parts partly broken away and others in horizontal section. Fig. 3 is a cross-section on line 3 3 of Fig. 1. Fig. 4 is a detail sectional view showing the followers and thimbles for the direct-acting spring. Fig. 5 is a detail view of one of the thimbles. Fig. 6 is a detail perspective view of the draft-iron. Fig. 7 is a detail perspective view of the side plates or stop-castings. 75

In said drawings, A represents the draft-timbers; A', the center sills; A², the cross-sills; A³, the buffer-block, and A⁵ the carry-iron.

B is the draw-bar of the coupler B'.

D is the sliding friction-draw-bar extension or draft-iron, the same being directly in line with the draw-bar and connected thereto by a clip or yoke b, passing through an eye d in the draw-bar extension or draft-iron, the cross-pivot d' of which eye is slightly rounded or beveled, so that the draw-bar and coupler may have the necessary slight lateral vibratory movement as well as a vibratory movement up and down. 90

F F are the side plates or stop-castings, fitting being the draft-timbers and securely attached thereto by bolts f.

The draft-iron D has a straight friction-face d² on one side, preferably its upper side, which is in sliding frictional engagement with the stationary friction plate or face G, said plate or face G being securely fixed or anchored on the side plates or stop-castings F F, but preferably made in a separate piece therefrom or not integral therewith. The draft-iron D has on its opposite side from the straight friction-face d² and preferably on its lower side double-inclined friction-faces d³ d⁴, which

coöperate with the double-incline friction-faces $h\ h'$ of the transversely-movable friction-block H, which is acted upon by the transversely-arranged spring K. The transversely-movable friction-block H has a barrel or flange h^2 to receive the spring K, and the spring K is supported at its lower end by a removable spring seat or cup K', which is removably secured to the side plates or stop-castings F by cotter bolts or pins K², having keys K³, the pins or bolts K² extending through suitable lugs f³ on the side plates or stop-castings. The side plates or stop-castings have transversely-extending guides f⁴ for the friction-block H to reciprocate in or on transversely while holding the same in position longitudinally in respect to the draw-bar or draft-iron. The side plates or stop-castings are provided directly opposite or above the friction-block and its transverse guides f⁴ with a longitudinal guide f⁵ to receive the longitudinally-arranged direct-acting spring N and its followers P P, the followers P P being preferably circular and the longitudinal guide f⁵ therefor preferably cylindrical in form. The guide f⁵ is preferably formed one-half upon each of the side plates or stop-castings F and has open ends to facilitate the insertion and removal of the spring N and followers P. The stops f⁶ f⁶ for the followers P P to abut against are preferably made in separate pieces and removable from the guide f⁵ and the side plates or stop-castings upon which said guide is formed. These removable stops f⁶ f⁶ may preferably also serve as bolts for bolting or securing together the two side plates or stop-castings F F. These bolts are preferably laterally removable from the guides f⁵ of the side plates or stop-castings, this being conveniently effected by providing the holes f⁷, through which the bolts extend, with lateral openings f⁸, through which the bolts may be removed laterally when their nuts are loosened. This prevents the draft-timbers or center sills from interfering with the removal of the bolts, as they would do if the bolts had to be withdrawn lengthwise instead of removed laterally.

The draft-iron D is provided with central upright wings d⁵ d⁵ for operating the followers of the longitudinal or direct-acting spring. Thimbles P', having sockets p to receive the ends of the rod or stem p², which extends through the spring N, are preferably inserted between the wings d⁵ and the followers P. A small spring N' may, if desired, be inclosed within the main spring N. To cause the direct-acting spring N to come first into action under either pulling or buffing strains and the transversely-acting spring and friction-block to come subsequently into action, the incline friction-faces d³ d⁴ on the draft-iron are more widely separated than the coöperating friction-faces h h' on the friction-block, thus leaving some play for partial compression of the longitudinal or direct-acting spring before the friction-block begins to compress

the transverse spring K, and as the downward or transverse movement of the friction-block H is somewhat less than that of the followers P, I prefer to so arrange the parts that the direct-acting spring N is slightly or partially compressed when applied or assembled, as this enables me to use springs of the same size or length and still have both fully compressed by the full movement of the draft-iron, and the strength of both is thus fully utilized.

The draft-iron D is provided with the central web d⁶, bridging the incline friction-faces d³ d⁴ to strengthen the draft-iron, and which web fits in a corresponding slot formed in the friction-block H.

I claim—

1. In a combined friction and direct-acting spring draft-rigging, the combination with a draw-bar and draft-iron in line therewith having a straight friction-face on one side and double-incline friction-faces on its opposite side, a transversely-movable friction-block having double-incline friction-faces engaging the double-incline friction-faces on the draft-iron, a transversely-arranged spring acting against said friction-block and a longitudinally-arranged direct-acting spring and followers therefor on the opposite side of the draft-iron from said friction-block, substantially as specified.

2. In a friction draft-rigging, the combination with a longitudinally-arranged direct-acting spring and followers therefor, of a transversely-movable friction-block and transversely-arranged spring acting against said block, of a draft-iron extending centrally between said longitudinal spring and said transverse spring and friction-block, substantially as specified.

3. In a friction draft-rigging, the combination with a draw-bar and draft-iron in line therewith having a straight friction-face on its upper side and double-incline friction-faces on its lower side, a transversely-arranged spring, a friction-block having double-incline friction-faces engaging said double-incline friction-faces on the draft-iron, a stationary friction plate or face engaging the straight friction-face of said draft-iron, a longitudinally-arranged spring and followers centrally above said draft-iron and friction-block, said draft-iron having central upright wings for operating said followers, substantially as specified.

4. In a friction draft-rigging, the combination with a draw-bar and draft-iron in line therewith having a straight friction-face on its upper side and double-incline friction-faces on its lower side, a transversely-arranged spring, a friction-block having double-incline friction-faces engaging said double-incline friction-faces on the draft-iron, a stationary friction plate or face engaging the straight friction-face of said draft-iron, a longitudinally-arranged spring and followers centrally above said draft-iron and friction-block, said

- draft-iron having central upright wings for operating said followers, and side plates or stop-castings having transverse guides for said transversely-movable friction-block and 5 longitudinal guides for the followers of said longitudinal spring, substantially as specified.
5. In a friction draft-rigging, the combination with a draw-bar and draft-iron in line therewith having a straight friction-face on its upper side and double-incline friction-faces on its lower side, a transversely - arranged spring, a friction-block having double-incline friction-faces engaging said double-incline friction-faces on the draft-iron, a stationary friction plate or face engaging the straight friction-face of said draft-iron, a longitudinally-arranged spring and followers centrally above said draft-iron and friction-block, said 15 draft-iron having central upright wings for operating said followers, and side plates or stop-castings having transverse guides for said transversely-movable friction-block and longitudinal guides for the followers of said 20 longitudinal spring, and removable stops for said followers, substantially as specified.
6. In a friction draft-rigging, the combination with a draw-bar and draft-iron in line therewith having a straight friction-face on its 25 upper side and double-incline friction-faces on its lower side, a transversely - arranged spring, a friction-block having double-incline friction-faces engaging said double-incline friction-faces on the draft-iron, a stationary 30 friction plate or face engaging the straight friction-face of said draft-iron, a longitudinally-arranged spring and followers centrally above said draft-iron and friction-block, said 35 draft-iron having central upright wings for operating said followers, and side plates or stop-castings having transverse guides for said transversely-movable friction-block and longitudinal guides for the followers of said 40 longitudinal spring and laterally-removable 45 stops for said followers substantially as specified.
7. In a friction draft-rigging, the combination with a draw-bar and draft-iron in line therewith having a straight friction-face on its upper side and double-incline friction-faces on its lower side, a transversely - arranged spring, a friction-block having double-incline friction-faces engaging said double-incline friction-faces on the draft-iron, a stationary 50 friction plate or face engaging the straight friction-face of said draft-iron, a longitudinally-arranged spring and followers centrally above said draft-iron and friction-block, said draft-iron having central upright 55 wings for operating said followers, and side plates or stop-castings having transverse guides for said transversely-movable friction-block and longitudinal guides for the followers of said longitudinal spring, and laterally-removable 60 stops for said followers serving also as bolts to clamp said side plates or stop-castings together, substantially as specified.
8. In a combined friction and direct-acting spring draft-rigging, the combination with a draw-bar and draft-iron in line therewith 65 having a straight friction-face on one side and double-incline friction-faces on the other side, a transversely-movable friction-block having double-incline friction-faces, a transversely - arranged spring acting against the same, a stationary friction-face, a longitudinally-arranged spring and followers therefor, central upright wings on the draft-iron for operating said followers, and side plates or stop-castings secured to and between the draft-timbers or center sills and provided with a transverse guide for said transversely-movable friction-block, and a longitudinal guide for the followers of said longitudinal spring, substantially as specified. 70
9. In a friction spring draft-rigging, a draft-iron having a straight friction-face on one side and double-incline friction-faces on the opposite side and provided with central upright wings for operating the followers of a longitudinal spring, substantially as specified. 75
10. In a combined friction and direct-acting spring draft - rigging, the combination with a draft-iron having a straight friction-face on one side and double-incline friction-faces on the opposite side, a transversely-movable friction - block having double - incline friction-faces, a longitudinally-arranged direct-acting spring and followers therefor, a removable stationary friction-plate, and central upright wings on the draft-iron for operating the followers of said longitudinally-arranged direct-acting spring, substantially as specified. 80
11. In a combined friction and direct-acting spring draft-rigging, the combination with a draft-iron having a straight friction-face on one side and double-incline friction-faces on the opposite side, a transversely-movable friction - block having double - incline friction-faces, a longitudinally-arranged direct-acting spring and followers therefor, a stationary friction-plate and central upright wings on the draft-iron for operating the followers of said longitudinally - arranged direct - acting spring, and removable thimbles interposed between said wings on the draft-iron and the followers, substantially as specified. 85
12. In a combined friction and direct-acting spring draft-rigging, the combination with a draft-iron having a straight friction-face on one side and double-incline friction-faces on the opposite side, a transversely-movable friction - block having double - incline friction-faces, a longitudinally-arranged direct-acting spring and followers therefor, a stationary friction-plate, and central upright wings on the draft-iron for operating the followers of said longitudinally - arranged direct - acting spring, and removable thimbles interposed between said wings on the draft-iron and the followers, said thimbles having sockets and a stem or rod fitting in said sockets and extend- 90

- ing through the longitudinally-arranged direct-acting spring, substantially as specified.
13. A pair of side plates or stop-castings having a transverse guide for a transversely-movable friction-block, and a longitudinal guide for the followers of a longitudinally-arranged spring, said last-mentioned guide being of cylindrical form and having open ends, substantially as specified.
14. A pair of side plates or stop-castings having a transverse guide for a transversely-movable friction-block, and a longitudinal guide for the followers of a longitudinally-arranged spring, said last-mentioned guide being of cylindrical form and having open ends and provided with removable stops for the followers, substantially as specified.
15. A pair of side plates or stop-castings provided with bolt-holes having lateral openings to enable the bolts for securing the same together to be laterally removed, substantially as specified.
16. A pair of stop-castings having each a transverse integral guide for a transversely-movable friction-block and an integral longitudinal guide for the followers of a longitudinally-arranged spring, said last-mentioned guide being of a case form to inclose the spring and followers, substantially as specified.

JOHN J. HENNESSEY.
